CLAIM

The ornamental design for a portion of housing for a communication device, as shown and described.

DESCRIPTION

FIG. 1 is a perspective view of an ornamental design of a portion of housing for a communication device showing our new design.

FIG. 2 is a front orthographic view thereof; and,
 FIG. 3 is a bottom orthographic view thereof.

The broken lines shown in FIGS. 1-3 are included for the purpose of illustrating environmental elements only and form no part of the claimed design.
